UNITED STATES PATENT OFFICE

WARNER I. CUBBERLEY, OF WASHINGTON, DISTRICT OF COLUMBIA, ASSIGNEE TO
BENNINGTON WAX PAPER COMPANY, OF BENNINGTON, VERMONT

ENVELOPE FOR WAX PAPER

Application filed May 16, 1927. Serial No. 191,722.

My present invention, in its broad aspect, has reference to improvements in packages or envelopes for wax paper, and the like, and more particularly it is my purpose to provide an envelope or package from which sheets of wax paper, or the like, may be readily withdrawn one at a time without disturbing the remaining sheets in the envelope or package.

10 I am aware that it has previously been proposed to cut an opening or the like in an envelope or package for wax paper, and the like, from which a single sheet of such paper may be withdrawn without disturbing the remaining sheets, but my present invention is designed to utilize a conventional envelope or package device without any specially cut openings or the like for the purpose. To this end I provide a pair of strips 20 which are attached by glue, or the like, across the mouth of the envelope or package and adjacent or slightly overlapping the usual V-shaped opening therein, so that one sheet of wax paper may be withdrawn from the mouth of the envelope or package and through the V-shaped opening while the remaining sheets are held within the envelope or package by the strips. Furthermore, it is my purpose to provide a construction wherein 30 the opening through which the single sheets of wax paper is withdrawn can be closed by the ordinary end folds or flaps of the package thereby dispensing with the necessity of providing an extra closing means for keeping the remaining sheets in a clean, sanitary condition.

Other and equally important objects and advantages will become apparent as the description of my invention proceeds, but while I have in the present instance defined for the sake of illustration an article of a certain specific form, it will be understood that I do not desire to limit myself except as may be indicated by the scope of the claims appended hereto and forming a part of this specification.

In the drawings wherein is illustrated an embodiment of my invention:

Figure 1 is a view of my envelope or pack-

age opened to expose the mouth thereof and the contents.

Figure 2 is a view of my package or envelope completely sealed up,

Figure 3 is a view of the blank from which my package or envelope is formed,

Figure 4 is a view of the first folding operation upon the blank to form the envelope or package,

Figure 5 is a view of the second folding operation, and places the wrapper in such condition that it is merely necessary to fold down the end flaps to complete the packaging of the contents,

Figure 6 is a perspective view of the mouth of my package or envelope showing a sheet of wax paper, or the like, being withdrawn therefrom.

In the several views of the drawings wherein like characters of reference are used to designate like or similar parts throughout the several views:

The numeral (1) designates an eight-sided blank adapted to be folded along the dotted lines 2-2 to form flaps (3) and (4). The outside edge of the flap (4) is preferably gummed as at (5). The respective side edges (6) and (7) of the flaps are cut at different angles from the ends (8) of the blank, the angle of the sides (6) being preferably 45° and the angles of the sides (7) preferably being about 60° so that when the flaps (3) and (4) are folded down as shown in Figure 4 the V-shaped exposed portion at one end will be greater than that at the other. The gummed portion (5) holds the flaps together.

The contents, which in the present case is a pad of waxed paper sheets (8) is placed between dotted lines (9)—see Figure 4—and the ends folded upon each other on dotted lines (10) to form end flaps (11) shown in Figure 5. To complete the envelope or package the end flaps (11) are folded down as shown in dotted lines in Figure 5 or as shown in the completed assembly of Figure 2, whereupon a strip of gummed paper or fabric (14) is attached to the ends to seal the package.

As shown in Figures 1, 5 and 6, a portion of the contents of the package, i. e., the waxed

sheets, is exposed through the V-shaped opening (12).

The type of package above described differs very little from the construction of an ordinary mailing envelope common on the market, and no novelty is claimed except in combination with my hereinafter described means for retaining the contents in the package after the end flaps (11) are unsealed so that one sheet of paper at a time can be removed without disturbing the remaining sheets.

To this end I provide a pair of strips of paper or fabric (13) which are sealed over the mouth of the envelope or package adjacent or partially overlapping the V-shaped opening (12). The strips are attached to the flaps (3) and (4) and the end flaps (11). Consequently the contents of the package cannot be removed as a whole, but since wax paper is inherently very soft and flexible, one sheet at a time can be pulled, as shown in Figure 6—from the mouth of the package through the V-shaped opening and between the strips (13). The remaining sheets will not thereby be disturbed. When the required number of sheets have been withdrawn one at a time the end flap is disposed in its original position to close the mouth of the package and the V-shaped opening (12) thereby to keep the contents clean and sanitary at all times. While I have described the opening (12) as being V-shaped it can obviously be any other shape desired, as square, semi-circular or the like, so also can the proportions and structure of the flaps and other details of the package be modified at will without departing from the spirit of my invention which is essentially in the peculiar adaptation of the strips (13) with an opening in the mouth of the envelope, and in the unique arrangement whereby the opening so formed is closed by an end flap of the package or envelope. The scope of my invention is therefore to be determined by the claims.

I claim:

1. A wrapper for sheets of wax paper and the like, and formed to permit removal of the contents, said wrapper having closure members adapted to be folded down to prevent removal of the contents, and spaced apart elements engaging the wrapper and one of the closure members and positioned to obstruct withdrawal of the bulk of the contents thereof while allowing removal of separate sheets of the contents one at a time.

2. A wrapper for sheets of wax paper and the like, said wrapper having closure members adapted to be folded down to prevent removal of the contents, and spaced strips of material engaging the wrapper and one of the closure members and positioned to obstruct withdrawal of the bulk of the contents thereof while allowing removal of the separate sheets of the contents one at a time.

3. A wrapper for sheets of wax paper and the like, and cut away to expose a portion of the uppermost sheet of paper, said wrapper having closure members adapted to be folded down to prevent removal of the contents and to cover the cut away portion, and elements engaging one of said closure members and disposed to either side of the cut away portion to obstruct withdrawal of the bulk of the contents thereof while allowing removal of separate sheets of the contents one at a time.

4. A wrapper for sheets of wax paper and the like, and cut away to expose a portion of the uppermost sheet of paper, said wrapper having end closure members adapted to be folded down to prevent removal of the contents and to cover the cut away portion, and strips of material engaging one of said closure members and said wrapper and disposed to either side of the cut away portion to obstruct withdrawal of the bulk of the contents thereof while allowing removal of separate sheets of the contents one at a time.

5. A wrapper for sheets of wax paper and the like having a mouth formed to expose a portion of the uppermost sheet of paper, a closure member adapted to be folded down to prevent withdrawal of the contents of the wrapper and to close the mouth, and strips of non-elastic material engaging the closure member and the wrapper and disposed to either side of the mouth to obstruct withdrawal of the bulk of the contents thereof while allowing removal of the separate sheets of the contents one at a time through the mouth.

6. A wrapper for sheets of paper having a mouth formed to expose a portion of the uppermost sheet, a closing flap for the mouth, and gummed strips extending across the mouth in two spaced apart places and attached to the wrapper and the flap to prevent removal of the contents while permitting removal of the sheets one at a time between the strips.

7. A wrapper for sheets of wax paper and the like comprising a body folded about the bulk of the paper and having end portions through which the bulk of the paper may be withdrawn, the end portions being folded over and down to prevent withdrawal of the bulk of the contents, said wrapper being cut away to expose a portion of the uppermost sheet of wax paper, and strips of material placed in parallel spaced relationship to each other and on either side of the cut away portion and attached to the wrapper and to one of the end portions to prevent removal of the bulk of the contents while permitting withdrawal of the paper through the cut away portion a sheet at a time.

8. A wrapper for sheets of wax paper and the like, comprising a portion folded about the bulk of the paper to retain the same and

having end portions through which the bulk of the paper may be withdrawn, the wrapper being cut away adjacent one end to expose a portion of the uppermost sheet of paper, and the end portions being folded over and down to prevent withdrawal of the bulk of the contents and to close the cut away portion, and strips of material attached to the wrapper and to one of the end portions and positioned to either side of the cut away portion to prevent removal of the bulk of the contents while permitting withdrawal of the paper a sheet at a time through the cut away portion.

15 In testimony whereof, I affix my signature hereunto.

WARNER I. CUBBERLEY.
